UNITED STATES PATENT OFFICE.

FREDERICK E. STRASBURG, OF RUMFORD FALLS, MAINE, ASSIGNOR TO
CONTINENTAL PAPER BAG COMPANY, A CORPORATION OF MAINE.

CUTTING MECHANISM.

No. 806,808.

Specification of Letters Patent.

Patented Dec. 5, 1905.

Application filed January 10, 1905. Serial No. 240,401.

To all whom it may concern:

Be it known that I, FREDERICK E. STRASBURG, a citizen of the United States, residing at Rumford Falls, in the county of Oxford 5 and State of Maine, have invented certain new and useful Improvements in Cutting Mechanism, of which the following is a specification.

This invention relates to cutting mechanism, particularly to that class of such mechanism as is employed for severing a continuous web of paper into blanks or sections of uniform and predetermined length.

In the drawings accompanying this specification is illustrated a machine embodying one form of my invention, wherein—

Figure 1 is a side elevation of the invention. Fig. 2 is a plan thereof; and Fig. 3 is a detail end elevation looking in the direction 20 of arrow B, Fig. 1, of the striker and the mechanism for the actuation thereof. Fig. 4 is an enlarged cross-section on line *a a*, Fig. 2, of the float, knife, and striker.

My invention is peculiarly applicable in 25 connection with paper-bag machines in which it is desired to sever a continuous paper tube into lengths suitable for bag-blanks. Such paper tubing may be a simple flat tube or it may be provided with an inwardly-folded 30 tuck in each side thereof.

The machine set forth in the drawings comprises side frames 2 3, in which may be supported the various parts of the mechanism.

At 1 in the left-hand end of the machine, 35 Figs. 1 and 2, is shown the delivery end of some suitable tube-forming mechanism. In the present instance this mechanism is illustrated as adapted to form paper tubing having inwardly-folded tucks in each side thereof 40 and comprises as one of its elements a float 4, necked down at 6 to pass through an opening between feed-rolls 7 8. This opening is formed by oppositely-disposed reduced portions 9 in said rolls. Float 4 lies within the 45 tucked paper tube and above the inwardly-folded tucks thereof and terminates at its forward end in a serrated edge 5. Said serrated edge preferably conforms to a straight line lying at right angles to the travel of the 50 paper tube. Directly above the forward end of float 4 is knife 10. Said knife is fastened by bolts 12 to cross-bar 11, and the ends of said cross-bar are supported in brackets 15 16, springing from uprights 13 14. Knife 10

is also provided with a serrated edge 17, preferably of a curved contour receding toward its center. Feed-rolls 7 8 are mounted upon shafts 18 19, supported in suitable bearings 36 in uprights 13 14 on side frames 2 3, respectively. Somewhat in advance of rolls 60 7 8 and to the right hand, Figs. 1 and 2, of serrated edges 5 and 17 is a second pair of feed-rolls 21 22, mounted upon shafts 23 24, turning in suitable boxes in uprights 25 26 on frames 2 3, respectively. Shaft 24 is preferably mounted in stationary bearings in said uprights; but shaft 23 I prefer to support in vertically-slidable boxes 20, and which boxes may be urged downwardly by springs 27. The tension of said springs may be governed by means of screws 28. Upper shaft 18, carrying roll 7, is mounted in slidable boxes urged downwardly by springs, all similar in construction and operation, respectively, to the parts just described in connection with shaft 23.

The driving mechanism of the machine is as follows: Mounted in boxes 29 30 on side frames 2 3, respectively, is main shaft 31. On the rearward end of said shaft is mounted 80 pulley 32 and gear 33. Said gear meshes with intermediate gear 34, which in turn meshes with gear 35 on shaft 19. Shaft 18 is provided with gear 37 for engagement with gear 35. Shafts 23 24 are provided with intermeshing gears 39 40, respectively, and gear 40 is driven from gear 35 through intermediate 38. Rolls 7 8 and 21 22 are illustrated as all of one diameter, and the gears just described are so proportioned as to 90 cause said rolls to revolve with equal surface speeds. On the forward end of main shaft 31 is secured miter-gear 41, meshing with a similar miter-gear 42 on shaft 43, supported at right angles to main shaft 31 in 95 brackets 44 45. Power may be communicated to pulley 32 by means of the usual belt. (Not shown.)

Intermediate the two pairs of feed-rolls 7 8 and 21 22 and having its path of action in a 100 plane contiguous to the serrated edge of knife or blade 10 and float 4 is mounted striker 46 for severing, in connection with said blade and float, any paper web or tube that may be fed thereto. The paper-tube-forming mechanism, feed-rolls, blade, and float hereinbefore described are old in the art, 105 and I do not claim them as my invention.

My invention pertains to the striker and particularly to an improved mechanism for operating it. The major part of said mechanism is mounted upon bracket 45, outstanding from and fast to side frame 2. On shaft 43 in said bracket is fixed gear 47, meshing on the one side with gear 48 and on the other side with gear 49, said gears 48 49 also being pivotally mounted in bracket 45 on shafts 50 51, respectively. Upon the forward end of shaft 50 is mounted crank-disk 52, bearing a crank-pin 53. On said pin is mounted a slideable block 55, having the longer pair of its opposite sides suitably grooved for engagement with ribs 56 on the inside of slot 57 in arm 54. By means of said crank arm 54 may be oscillated on pivot 58 in bracket 59 toward and away from the path of the paper to be severed. Upon the forward end of shaft 51 is mounted another crank-disk 60, similar to disk 52 on shaft 50. Crank-disk 60 is provided with a hole 61, eccentric to the axis of rotation of said disk, and in said hole 61 is mounted pivot-pin 62 of grooved block 63. Groove 64 in said block is preferably provided with undercut sides 65 for sliding engagement with complementarily-fashioned sides 67 of shank portion 66 of striker 46. The rearward end 70 of striker 46 is pivoted within the bifurcated free end of lever 54 on bolt 68.

By means of the mechanism just described the cutting edge 71 of striker 46 may be driven upwardly at high speed across the path of the paper web or tube and then withdrawn and moved backwardly and downwardly at slower speed around that path to repeat the operation, as indicated by the dotted line P, Fig. 3. At 46^a said striker is shown in dot-and-dash lines in one position of its backward path.

The operation of my improved machine is as follows: The web of paper or paper tubing having been fed into the machine between rolls 7 8 and forwardly beyond serrated edges 5 and 17 and into the grip of rolls 21 22, power is applied and the machine started. The paper thereupon is moved forwardly by means of said rolls, and striker 46 moves upwardly toward the position shown in Fig. 3. At this time crank-pin 53 is at the right of axis 50, and arm 54 is thereby swung to the right on its pivot 58, and through connecting-pivot 68 striker 46 is slid to the right in block 63, with its cutting edge 71 ready to engage the paper as said paper passes off float 4 and under edge 17 of knife 10. At the same time crank-pin 62 of grooved block 63 is moving upwardly at the left-hand side of axis 51, thereby causing said striker 46 to move upwardly, as indicated in Fig. 3. Furthermore, said striker will travel at relatively high speed at this portion of its stroke because of the nearness of crank-pin 62 to pivot-pin 68. Continuing its upward travel, 65 said striker will engage the paper at high

speed and sever it against the edges of the float and knife, the paper being in the grip of the two pairs of rolls 7 8 and 21 22. Said striker will then continue its upward movement until crank-pin 62 reaches a position 70 directly over axis 51, Fig. 3, and at which time crank-pin 53 will have reached a position directly below axis 50. The striker will then have moved to dotted position 46^a and point 75 thereof will have reached position p 75 in the dot-and-dash path of Fig. 3. Crank-pins 62 and 53 continuing their respective rotations, striker 46 will be withdrawn to the left and downwardly at a comparatively slow speed and then moved forwardly and still 80 downwardly back to position p p, Fig. 3, ready to repeat the operation just described.

I claim—

1. The combination of a knife, a striker slidably mounted in a bearing, said bearing 85 pivotally mounted for movement in a circular path, an oscillatable arm, the rear end of said striker pivoted to the free end of said arm, means to cause the bearing to travel in a circular path and means to oscillate the 90 arm, all combined and operating together substantially as described.

2. The combination of a knife, a striker slidably mounted on a crank, an oscillatable arm, one end of the striker being pivoted to 95 the free end of the arm, and a second crank to oscillate the arm, all combined and operating together substantially as described.

3. The combination of a knife, a striker mounted for universal plane movement in 100 the plane of its length, an oscillatable arm, the rear end of the striker being pivoted to the free end of said arm, means to oscillate the arm and means to oscillate the striker substantially normal thereto, all combined 105 and operating together substantially as described.

4. The combination of a knife, a striker 46 mounted for universal plane movement in the plane of its length, a crank to oscillate 110 the striker, an arm 54 having one end pivoted at 58 and the other end pivoted to the striker, and a second crank to oscillate the arm, all combined and operating together substantially as described. 115

5. The combination of a knife, two cranks, a striker slidably mounted on one of the cranks, an oscillatable arm actuated by the other crank and means to slide the striker from the oscillatable arm, all combined and 120 operating together substantially as described.

Signed at Rumford Falls, in the county of Oxford and State of Maine, this 6th day of January, 1905, in the presence of two subscribing witnesses.

FREDERICK E. STRASBURG.
